UNITED STATES PATENT OFFICE

GLEN E. TAYLOR, OF HOUSTON, TEXAS

PROJECTING MACHINE

Application filed August 24, 1926. Serial No. 131,177.

This invention relates to new and useful improvements in a projecting machine.

One object of the invention is to provide a machine for projecting an image, of any character, and at the same time moving the image bodily about the screen, as desired, the machine having been specifically designed for moving the image of an aeroplane or other air craft about an elevated screen or ceiling so as to simulate the movements of the actual craft in flying.

Another object of the invention is to provide a novel means for mounting and operating the apparatus.

A further object of the invention is to provide a machine of the character described, equipped with means for so mounting the film therein as to project a true proportioned image, said film being capable of adjustment in its holder so as to bring it into the correct angular relation with the screen or ceiling onto which the image is projected.

With the above and other objects in view this invention has particular relation to certain novel features of construction, operation and arrangement of parts, an example of which is given in this specification and illustrated in the accompanying drawings, wherein:

Figure 1 shows a side elevation of the device, partly in section.

Figure 2 shows a front elevation.

Figure 3 shows a sectional view taken on the line 3-3 of Figure 1.

Figure 4 shows a sectional view taken on the line 4-4 of Figure 1, and

Figure 5 shows a plan view of a film whose image is to be projected.

Referring now more particularly to the drawings, wherein like numerals of reference designate similar parts in each of the figures the numeral 1 designates the supporting platform of the machine mounted on which is a supporting framework 2 having vertically aligned bearings in which the vertical shaft 3 is rotatably mounted. The shaft 3 has a screw gear 4 fixed thereon which is in mesh with and driven by the worm gear 5 fixed on the transverse shaft 6. One end of the shaft 6 has a spur gear 7 fixed thereon which

is in mesh with and driven by a larger spur gear 8 which is fixed on the shaft of the motor 9. Through the mechanism described the shaft 3 may be slowly rotated.

The numeral 10 designates a substantially enclosed housing, preferably formed of sheet metal and whose top is formed with the side outlet flues 11, 11, to permit the escape of hot air from within the housing. The housing 10 is adjustably mounted on a supporting platform 12 so that it may be balanced on the shaft 3 and said platform is mounted on the upper end of said shaft and is connected thereto by means of a hinge joint 13. Within the housing there is an electric light 14 which is mounted in front of the reflector 15, supported by the bracket 16, all within said housing. This reflector is adjustable toward and from the light 14 so as to vary the intensity and distribution of the light. Fastened to the front end of the housing, in alignment with the light 14, there is a lens telescope 17 having the usual objective lens 17' and between said light 14 and telescope 17 and mounted within the housing are the reversely arranged plano-convex condensing lenses 18. The film 19, carrying the image to be projected, is insetted in the suitable box-like holder 20 in front of the lens 18. This holder has a slide cover 20' for opening and closing the same.

The film 19 may be given any angle desired, relative to the axis of said lenses 17', 18 so that said angle will correspond to the angle of said axis with the surface of said screen or ceiling and the position of the film in its holder may be varied until a correct and proportionate image is obtained.

Fastened to the shaft 3 there is a disc 21 formed of fiber or other non-conducting material whose under side has the concentric arcuate copper strips 22 and wiring 23 is connected to these respective strips and forms a circuit through the filament of the light 14. Connected to the wiring, through which the current is supplied to the motor 9, there is the wiring 24 which terminates in the tongues 25, 25, which are carried by the upper end of the framework 2 and are adapted to contact with the respective strips 22 to complete an elec-

trical circuit from the main feed wires to the filament of the light 14. This circuit is alternatively completed and broken as the disc 21 rotates. It is of course obvious that by 5 making the strips 22 circular the circuit will be continuous. The hinge 13 is adjustable so that the image may be projected at any angle desired and the image will be bodily moved about on the overhead screen describing a 10 circle as the shaft 3 rotates.

What I claim is:

1. A projecting machine including a supporting platform, a frame work on said platform having vertically aligned bearings, a 15 vertical shaft rotably mounted in said bearings, a motor, a train of gears operatively connecting the motor with said shaft, a platform hinged to the upper end of said shaft, an inclosed housing adjustable on said last mentioned platform, means within the housing for projecting an image, said means including an electric light, a disc fastened to said shaft formed of nonconducting material, strips fastened to said disc, wiring connected 20 to said strips and forming a circuit through the light, tongues carried by said frame which contact intermittently with said strips as the shaft rotates, and electrical conductors connected to said tongues.
2. A projecting machine including a supporting frame work, having vertically aligning bearings, a rotatable shaft mounted in said bearings, a motor, gearing connecting the motor with said shaft, a supporting platform 25 hinged to the upper end of said shaft, a housing on said platform, and adjustably connected thereto, an electric light within the housing, a reflector behind the light, a lens telescope fastened to the front side of the housing, in alignment with said light, reversely 30 arranged plano-convex condensing lenses between said light and telescope, a box like holder in front of said condensing lenses, a film in said holder, current conductors forming a circuit through the light filament and 35 means carried by the shaft and framework, respectively for completing a circuit through 40 said conductors.

In testimony whereof I have signed my 50 name.

GLEN E. TAYLOR.
